UNITED STATES PATENT OFFICE.

LOUIS L. JOSEPH, OF CHICAGO, ILLINOIS.

KNIFE.

1,128,788.

Specification of Letters Patent. Patented Feb. 16, 1915.

Application filed July 25, 1914. Serial No. 853,204.

To all whom it may concern:

Be it known that I, LOUIS L. JOSEPH, a citizen of the United States, residing at Chicago, in the county of Cook and State of Illinois, have invented a new and useful Improvement in Knives, of which the following is a specification.

My invention relates more particularly to improvement in the means for fastening in place against the sides of the knife the ornamental handle-sections thereof, as, for example, those made in part of celluloid; my object being to provide novel and simple means for this purpose which will enable the knife to be manufactured at relatively low cost and present the desired neat appearance, eliminating the exposure to view of rivets, or the like, on the outside of the handle-sections of the knife.

Referring to the accompanying drawing—Figure 1 is a face view of a folding pocket-knife constructed in accordance with my invention. Fig. 2 is an edge view of the same. Fig. 3 is an edge view thereof with the handle-sections removed. Fig. 4 is a view of the inner face of one of the similar handle-sections of the knife. Fig. 5 is a similar view of one of the similar side-plates of the knife. Fig. 6 is an enlarged section taken at the line 6 on Fig. 4 and viewed in the direction of the arrow; and Fig. 7, a section taken at the line 7 on Fig. 1 and viewed in the direction of the arrow.

In the knife illustrated the side-plates thereof are represented at 8, two of these plates being provided with blades 9 and 10 and the usual spring-bar 11 interposed therebetween, these parts being connected together by rivets 12, 13 and 14, the rivets 12 and 13 passing through the ends of the plates 8 and the blades 9 and 10 and pivotally connecting the blades with the side-plates, and the rivet 14 passing through these plates intermediate their ends and through the spring-bar 11, the ends of the latter being free to be sprung and coöperating with the blades as is usual in knives of this general type.

The handle-sections of the knife are represented at 15, these sections in the construction illustrated having their exposed surfaces covered with sheet celluloid, or any other suitable flexible material, represented at 16, though the handle-sections may be otherwise formed as desired. In the case of the structure shown, the handle-sections 15

are formed of plates 17 having rearwardly extending continuous flanges 18 along their marginal edges, with the sheets of celluloid 16 extending over the outer sides of the sections 15 and turned rearwardly over the flanges 18 and crimped into the position shown in Fig. 6, whereby the celluloid sheets are firmly attached to the plates 17 and extend over the exposed surfaces 65 thereof.

The plates 17 are provided on their inner surfaces with lugs 19 preferably formed by partially slitting the metal of the plates 17 and turning it back to provide the lugs as 70 represented. The plates 17 are of such proportions that after applying the celluloid covering thereto the plates 17 may be applied to the side-plates 8 to telescoping condition, as represented in Fig. 7, the plates 75 8 containing slots 20 which are adapted to register with the lugs 19 and receive the latter upon applying the plates 17 to the plates 8 as stated, the lugs 19 projecting through the plates 8 into the interior of the knife, 80 and being bent against the inner surfaces of the plates 8 to clench them together, as represented in Fig. 7, it being preferred that the central sections of the plates 8, containing the slots 20, be slightly outwardly offset as represented at 21, whereby the deflected ends of the lugs 20 shall lie in the recesses thus formed and within the planes of the main portions of the inner sides of the plates 8 and thus not in any way obstruct the blades.

It will be noted from the foregoing that no rivets or other fastening means are exposed on the outer surfaces of the handle-sections, and thus the appearance of the 95 knife is not detracted from by this cause. Furthermore, the parts of the knife may be quickly assembled and the completed knife is very strong, and danger of the handle-sections separating from the body of the 100 knife is reduced to the minimum.

While I have illustrated and described a particular embodiment of my invention, I do not wish to be understood as intending to limit it thereto as the same may be variously modified and altered without departing from the spirit of my invention.

What I claim as new and desire to secure by Letters Patent is—

1. In a knife, the combination of a pair 110 of plates secured together in spaced relation with a blade therebetween and con-

- taining openings, handle-sections on said plates, and integral projections on said handle-sections extending through the openings in said plates and interlocking with the latter against the inner sides thereof. 6. In a knife, the combination of a pair of plates, means securing said plates together in spaced relation with a blade therebetween, plates flatwise opposing said pair of plates, and a covering for each of said last-named plates extending over and turned under the edges of the latter. 45
2. In a knife, the combination of a pair of plates secured together in spaced relation with a blade therebetween and containing openings, with the inner sides of said plates recessed at said openings, handle-sections on said plates, and projections on said handle-sections extending through the openings in said plates and interlocking with the latter against the inner sides thereof. 7. In a knife, the combination of a pair of plates secured together in spaced relation with a blade therebetween and containing openings, handle-sections on said plates, projections on said handle-sections extending through the openings in said plates and interlocking with the latter against the inner sides thereof, and a covering extending over and turned under the edges of said handle-sections and covering the securing means of 50 the knife. 55
3. In a knife, the combination of a pair of plates secured together in spaced relation with a blade therebetween, said plates being recessed by having their central portions outwardly offset and containing openings in said portions, handle-sections on said plates, and projections on said handle-sections extending through the openings in said plates and interlocking with the latter against the inner sides thereof. 8. In a knife, the combination of a pair of plates secured together in spaced relation with a blade therebetween, handle-sections containing recesses on their inner faces 60 in which said plates are located, and means for securing said handle-sections to said plates. 65
4. In a knife, the combination of a pair of plates, means securing said plates together in spaced relation with a blade therebetween, plates flatwise opposing said pair of plates, means securing said last-named plates to said pair of plates, and a covering for each of said last-named plates secured between adjacent plates. 9. In a knife, the combination of a pair of plates, rivets, or the like, securing said plates together in spaced relation with a blade therebetween, said plates having their central portions outwardly offset and containing openings in said offset portions, handle-sections fitting against said plates 70 and provided with lugs struck from said sections and extending through the openings in said plates with their inner ends bent into overlapping engagement with the inner faces of said plates, and a covering extending over said handle-sections and crimped in about the outer edges thereof. 75
5. In a knife, the combination of a pair of plates containing openings, means securing said plates together in spaced relation with a blade therebetween, plates flatwise opposing said pair of plates and carrying lugs extending into said openings and interlocking with said pair of plates at the inner faces of the latter, and a covering for each of said last-named plates secured at its periphery between the plates. 80
